UNITED STATES PATENT OFFICE.

EDGAR B. SYMONS, OF MILWAUKEE, WISCONSIN.

RING-ROLL MILL.

1,217,525.

Specification of Letters Patent. Patented Feb. 27, 1917.

Application filed April 30, 1913. Serial No. 764,489.

To all whom it may concern:

Be it known that I, EDGAR B. SYMONS, a citizen of the United States, residing at Milwaukee, in the county of Milwaukee and 5 State of Wisconsin, have invented a certain new and useful Improvement in Ring-Roll Mills, of which the following is a specification.

My invention relates to improvements in 10 pulverizing or reducing or crushing machinery and is illustrated more or less diagrammatically in the accompanying drawings, wherein—

Figure 1 is a vertical section;

Fig. 2 is a horizontal section along line 2—2 of Fig. 1;

Fig. 3 is a horizontal section along line 3—3 of Fig. 1; and

Fig. 4 is a side elevation with parts 20 broken away and in section of a roller cage and supporting and contiguous parts.

Like parts are indicated by the same letters throughout the several figures.

The base A, adapted to be supported in 25 the usual manner on a framework A¹, contains and supports in the center thereof a housing or inner frame A² supported therefrom by the arms A³, A³ and a tubular cylindrical support A⁴. The base A is provided with an extension A⁵ which contains 30 a bearing A⁶. The housing or frame A² contains a bearing A⁷ in line with the bearing A⁶. A drive shaft A⁸ is supported in the bearings A⁶, A⁷ and is adapted to be 35 driven from any suitable source of power transmitted through a pulley A⁹. A miter pinion A¹⁰ is keyed to the opposed end of the drive shaft A⁸. A plug A¹¹ is screw-threaded into a collar A¹² which collar is 40 provided with a shoulder A¹³ and is removably mounted in the wall of the frame or housing A². A bearing block A¹⁴ is set into the plug A¹¹ in opposition to the end of the shaft A⁸. A set screw A¹⁵ is screw-threaded in the plug A¹¹ in opposition to the block A¹⁴ and is adapted to limit the longitudinal movement of the shaft A⁸. A lock nut A¹⁶ is provided to hold the set screw in position.

50 Centrally located in and upwardly projecting from the frame or housing A² is the lower, central, hollow, bearing hub B. This hub contains an inner bearing sleeve B¹ provided with a horizontally disposed bearing surface B² and a downwardly extending sleeve or collar B³ in which is screw-threaded a ring B⁴. On this ring is mounted a

bearing plate B⁵ pinned against rotation. A rotatable bearing plate B⁶ rests upon the bearing surface B² and rotates thereupon 60 and is provided with a downwardly projecting, centrally disposed lug B⁷ to the end of which is pinned a bearing foot B⁸ in opposition to the bearing plate B⁵. An oil passage B⁹ leads upwardly from the space 65 in the housing A² beneath the hub B through the parts B⁵, B⁸, B⁷ and B⁶. Upon the bearing plate B⁶ and pinned thereto so as to rotate with it is the roller cage which I am now about to describe.

70 This roller cage consists of a base or foot plate C resting upon and pinned to the bearing plate B⁶ and provided about its periphery with the two concentric, downwardly depending flanges C¹, C² located one on either side of a flange C³ extending upwardly from the frame or housing A². This foot plate has downwardly depending therefrom a collar C⁴ concentric with and surrounding the hub B to which is rigidly attached the miter gear C⁵ in mesh with the miter pinions A¹⁰. A somewhat similar head plate C⁶ is located above and substantially concentric with the foot plate C, being bound thereto by the three pipes C⁷. This 80 head plate is provided with an upwardly projecting guide lug or hub C⁸ which is loosely mounted in and guided by a bearing member subsequently to be described. The head and foot plates together with the pipes 90 which serve both to bind them together and also as oil conduits form a roller cage in which the crushing rollers are mounted. The pipes C⁷ are mounted in the projections C⁹ projecting upwardly or downwardly as the 95 case may be from the plates C, C⁶. These projections or supports have opposed parallel surfaces C¹⁰, C¹¹ parallel with the radii. Guide yokes C¹² are slidably adjustably mounted upon these surfaces, being held in 100 position and slidable thereon by means of the screwthreaded sleeves C¹⁴ screw-threaded in the supports C⁹ and containing the screws C¹⁵ slidably and rotatably mounted therein provided with screw-threaded heads C¹⁶ also screw-threaded in the supports C⁹. The sleeves C¹⁴ have truncated spherical ends or heads C¹⁷ in opposition to the plano-concave washers C¹⁸ in slidable contact with one side of the lugs C¹⁹ projecting from the 110 yokes C¹². A nut C²⁰ is screw-threaded on the screw C¹⁵ in opposition to the plano-convex washer C²¹ which washer is in engagement with a plano-concave washer C²²

70

110

in opposition to the opposed side of the lug C¹⁹. By manipulating the screws, sleeves and nuts the position of the guide yokes may be adjusted at will, the washer and screw being screwed into position separately and then jammed together and the lug being then clamped in position with respect to the screw.

These yokes C¹² have slidably mounted between them and guided by them the rectangular bearing blocks D, D⁷ whose slideable motion in a radial direction is limited at the outside by the cross member D¹ of the yoke and shims D², D³ which may be placed in front of the cross member. These blocks are pressed outwardly against these shims or cross member by means of the two springs D⁴, D⁵ which are compressed between the bearing blocks D, D⁷ and the saddle D⁶. The position of this saddle is adjusted with respect to the yoke by means of the long cap screws D⁷⁰ which are screw-threaded in the saddle; thus the pressure of these springs may be adjusted at will. The bearing blocks D, D⁷ provide bearings for the roller shaft D⁸. The lower bearing blocks D⁷ form a substantially flat bearing spot D⁹ slideable upon the foot plate C. The bearing block D has a spherical end D¹⁰ in slideable contact with the head plate C⁶. The shaft D⁸ is supported at its lower end by an end bearing D¹¹. The bearing block D⁷ has immediately above it an annular, truncated, conical collar D¹² and immediately below and in slideable and rotatable contact with the lower end of the bearing block D a collar D¹³ having a downwardly depending apron D¹⁴. The bearing block D carries a downwardly projecting extension D¹⁵ closed at its lower side by the screw-threaded block D¹⁶ which block has a sleeve D¹⁷ surrounding the shaft and provided with an annular ring D¹⁸ in opposition to the apron D¹⁴. This projection D¹⁵ forms an oiling ring support or housing and is provided with an outwardly projecting extension D¹⁹ which terminates at its outer end in a pipe connection D²⁰ which pipe connection is located at the point farthest removed from the center of rotation. The bearing block D⁷ projects upwardly above the guide yoke and has an eccentric enlargement D²¹ to form an oil channel leading away from and surrounding the truncated conical flange D²². This oil channel terminates in a pipe connection D²³. A pipe D²³ leads from the pipe connection D²⁰ through the pipe connection D²². A flexible tube D²⁴ leads from the pipe connection D²² to the interior of the housing A² through the foot plate C.

The shaft D⁸ carries rigidly attached thereon the roller block E. This roller block has two upwardly diminishing truncated conical surfaces E¹, E² the upper surface

being substantially smaller at its largest diameter than the lower surface at its smallest diameter. The cylindrical roller apron E³ has two opposed truncated conical surfaces, one of them E⁴ of substantially the same dimensions as the surface E¹. The roller apron thus rests upon the surface E¹ and is centered thereupon by a truncated conical wedge E⁵ having two truncated conical surfaces, one in opposition to the surface E² and the other in opposition to the surface E⁶ of the roller apron E³. The nut E⁷ is in screw-threaded engagement with the shaft D⁸ and overlies the wedge E⁵ and may be rotated to force the wedge E⁵ downward to clamp the apron in position. A lock nut E⁸ is also in screw-threaded engagement with the shaft D⁸ and adapted to lock the nut E⁷ in position. A pipe E⁹ centrally located in the foot plate C and in line with the passage B⁹ leads upwardly into the center of the hub C⁸ and is provided at two points along its length with the three-way connections E¹⁰ from which lead the three pipes E¹¹ which pipes discharge respectively into the housings D²¹ and D¹⁹ to oil the respective bearings. A passage E²¹ leads radially out from the conduit E¹² which conduit is in line with and in connection with the pipe E¹⁰ to the oil groove E¹³ in the outer wall the hub C⁸. The flange E¹⁴ on the head plate C⁶ surrounds the flange E¹⁵ on the bearing sleeve E¹⁶ which sleeve surrounds the hub C⁸, and the oil passage E¹⁷ leads from the oil sleeve E¹⁸ which is closed by this flange and surrounds the hub C⁸ to the pipes C⁷, thus completing the oil circuit. The hub C⁸ has pinned therein the shaft E¹⁹ on the upper end of which is mounted against rotation the distributing disk E²⁰.

The base A supports the split annular frame F made up of two semicircular segments bolted together by the tie bolts F¹, F². This frame contains the annular crushing ring F³ backed in the frame by any suitable zinc or other soft metal backing F⁴ and held in position by the annular flange F⁵ upon which the ring rests and by the annular flange F⁶ projecting from the ring surrounded by the backing material and overlying a portion of the top of the frame. This ring is generally upwardly and outwardly inclined so that its lower diameter is slightly less than its minimum upper diameter and considerably less than its maximum upper diameter, owing to the fact that the ring is provided in its upper half with the downwardly diminishing channels or grooves F⁷ which substantially increase its maximum upper diameter beyond its minimum diameter. It will be noted thus that the distance between the ring and roll is slightly greater at top than at bottom and that this difference is more marked as between the roll and

the bottom of the grooves than as between the roll and the surface of the dividing lines between the grooves. The housing F^8 is supported on the frame F , being centered thereon in any suitable manner not shown and held in position by the bolts F^9 . This housing is of substantially larger diameter than the crushing ring and therefore rests on the outer extremity of the upper flange F^{10} of the frame F . Since the crushing ring F^3 projects upwardly above the top of the frame F , it will be noted that a pocket is provided about the base in which the material can fall and in which it will be retained so that any further material falling down into this pocket will drop upon material already there and will not tend to wear away the housing or frame F . A shield F^{11} is mounted in the housing F^8 , being supported therein by the webs F^{12} . This shield has a downwardly extending apron F^{13} which shades into parallelism with the inner wall of the housing F^8 and which assists in inclosing the upper end of the roller cage but terminating short of the top of the crushing ring, thus leaving room for the passage of material. The bearing sleeve E^{16} is supported in this shield F^{11} and being centered therein tends to prevent the roller cage from getting out of alignment.

A feed housing G rests upon the upper wall of the housing F^8 , is closed by a top G^1 , and carries a feed hopper G^2 which hopper discharges through a spout G^3 into an adjustable discharge chute G^4 which chute discharges the material onto the distributing feed plate E^{20} . This chute G^4 is adjusted vertically in position by the bolts G^5 an adjustment of which will change the distance between it and the feed plate and thus limit or control the amount of material fed into the machine.

The end of the bearing A^6 is inclosed by a jacket H which is provided with an inwardly extending sleeve H^1 terminating in an outwardly projecting flange H^2 which flange is in slidable contact with a collar H^3 on the shaft A^8 which collar is provided with an outwardly projecting apron H^4 . A pipe H^5 leads from the lowest point in the housing A^2 beneath the pinions A^{10} to the jacket H . A pipe H^6 leads from the jacket H to an oil reservoir not shown. The conduit H^7 leads from the housing A^2 surrounding the gear C^5 into the interior of the cylindrical passage A^4 surrounding the shaft A^8 , and all the oil may be discharged thence through the bearings A^6 , A^7 either to the jacket H or back to the housing A^2 adjacent the miter gear A^{10} . A pipe H^8 leads from an oil pump not shown to the chamber H^9 beneath the foot bearing B^8 , and oil may pass thence up through the pipe E^{10} and the distributing system.

The base A is provided with a hand hole

J closed by a shutter J^1 by removing which access may be had to the lower roller bearings to adjust them, and the frame or housing F^8 is provided with a hand hole J^2 closed by a shutter J^3 whereby access may be had to the upper bearings to adjust them so that the ordinary working adjustment may be very easily and conveniently made without dismounting the machine.

It will be evident that, while I have shown in my drawings an operative device, still many changes might be made in size, shape and arrangement of parts without departing materially from the spirit of my invention. I wish, therefore, that my drawings be regarded as in a sense diagrammatic.

The use and operation of my invention are as follows:

Material to be crushed is fed into the hopper G^2 in such quantity as to keep it, the chute G^3 and the feed spout G^4 completely filled at all times. This material passes out from the feed spout G^4 , down over the feed disk or plate and is by it projected centrifugally down along the surface of the shield F^{11} passing out over its outer edge down between the apron and the housing, sliding down over the mass of material which has meanwhile become located about the periphery of the crushing ring and thence down through the ring. Since the roller cage is meanwhile being rotated, being driven as it is by the drive shaft from below, the material as it falls down across the crushing ring will be exposed to a rapid succession of violent crushing blows by successive rolls as they pass about the ring. The rotational speed of the cage will be such that a number of blows will be dealt to each particle during the time which it takes it to fall freely from the top to the bottom of the ring. The material will, of course, be arrested and brought to a full stop by each blow and will subsequent to such blow fall freely until the next blow occurs. The friction between the rollers of the cage as they travel about the surface of the ring and the material being reduced will cause them to immediately commence to rotate, and before very many rotations of the cage the rollers will be rotating at such a rate that their peripheral velocity bears such relation to the peripheral velocity of the cage that they will roll along the crushing ring without any appreciable slipping component. Thus the material will be crushed between the ring and roller by a blow which has no grinding action whatever but purely a crushing effect.

The function of the grooves or slots in the upper portion of the ring is to hold the material against sliding displacement about the ring and to assist it in maintaining that frictional relation to the ring which is necessary to maintain the rotation of the rolls about their several axes while traveling

along the ring. It will be noted that the two ends of the shaft supporting the roll are both free to move radially. Thus the roll may assume within reasonable limits any 5 angular position in a radial plane, the result of this being that the machine will not be damaged by the passage of uncrushable material or material such as nuts, bolts and metal parts which might otherwise do dam- 10 age.

The rollers are pressed outwardly by the springs and this prevents any bumping of the rolls, since it gives a constant outward pressure in addition to the centrifugal outward force which may vary owing to the 15 possibility of variations in speed. The spring acts merely as a reinforcement or a pressure reservoir to minimize the effect of momentary changes in pressure and to permit 20 the rolls to exert sufficient pressure on the material while starting up to enable them to be rotated in response to that pressure as above indicated.

Since the angular position of the rolls 25 may be adjusted, it is possible to vary the length of the crushing stroke and the size of product. If the material is very soft and a very large capacity is desired, the rolls will be adjusted so that their angularity with respect 30 to the ring will be great. If the material is very hard and a very fine product is required, the material fed will, of course, have to be comparatively small and the rolls will be placed at a very slight angle with respect 35 to the ring and a great number of strokes will be given to each particle as it falls, and the distance traversed by each particle between strokes will be very small and thus the reduction while gradual will be 40 very complete. The machine, therefore, may be made by adjusting the angle between the roll and ring to give any desired product.

The operation of the oiling system is as follows:

45 Oil is pumped from the reservoir by a pump, which I have not shown as any pump will do, into the small central chamber in the housing at the bottom, passes up through the central supporting bearings into and 50 through the central pipe. From this pipe some of the oil is discharged through the oiling conduits and pipes to bearings at the lower ends of the roll shafts, some of the oil is discharged to the bearings at the upper 55 ends of the roll shafts and the remainder of the oil is discharged to and through the loose bearing in which the upper hub travels. The oil which is fed to the shaft bearings leaves them through the housings D¹⁹ and D²¹ and is discharged through the pipes D²³ and D²⁴ back to the housing A². The oil which is fed to the bearing around the hub C⁸ passes back through the pipes C⁷ to the interior of the housing A² and this oil 60 passes out from the housing A² either

through the pipe H⁶ or along the shaft A⁸ to the jacket H and thence to the reservoir from which it is subsequently re-pumped through the system. It will be noted that thus every bearing is kept flooded with oil 70 at all times, and by this oil flood the bearings are protected from dust and grit and what little dust and grit may get into the oil will be immediately washed by the oil away from the bearings and carried with 75 the oil down to the oil reservoir where it may be easily and conveniently separated out from the oil by any suitable means.

The operation of the means for adjusting the tension of the springs and means 80 for adjusting the ends of the roll shafts radially it is thought has already been adequately explained.

The function of the ball and socket connection between the flanges on the guide 85 yoke, the holding bolts and sleeves is merely to prevent binding in case the yoke should not be absolutely in line and to permit of rapid adjustment without necessitating any very close attention on the part of the operator 90 who is, of course, likely to be more or less unskilled.

The feed plate as it rotates, of course, is free to throw material in any direction about the inside of the housing, and it does feed 95 the material in a substantially continuous sheet in all directions down across the shield so that it frequently is fed from the shield down over and across the crushing ring in a substantially continuous, thin, annular 100 stream, and it is this continuous, thin, annular stream that the rolls pass over as they rotate and are carried along the ring surface. Thus the material being acted upon by the roll at any one time is substantially little 105 in amount and is never banked up on the ring so that no power is lost in packing material which subsequently merely acts as a shield for material to be crushed.

The only wearing parts are the crushing 110 ring and the jackets on the crushing rolls and these may be conveniently removed. To remove the crushing ring it is only necessary to remove the upper housing and break open the split frame ring to free it from the 115 crushing ring. The ring can then be removed. If any difficulty is discovered the soft backing may be cut away or melted away as the case may be thus completely 120 freeing the parts without difficulty. The jacket on the roll may be removed by back- 125 ing off the two nuts, namely, the lock nut and the holding nut which are screw-threaded on the roll shaft. This will permit the ring wedge to be freed and then the jacket itself may be removed from the core.

The notches or grooves or transverse channels in the upper portion of the crushing ring have inclined surfaces, thus forming what is in effect, two separate zones, one 130

made up of crushing surfaces sharply inclined, the other zone below made up of the smooth, gradually inclined space of the ring less sharply inclined. The transverse channels of course act as holding surfaces to hold the material as it is fed into the machine, and the pockets around the top also assist in overcoming any spiral movement of the material.

I claim:

1. In a crushing machine a roller cage containing crushing rollers, a support bearing at the bottom of said cage upon and about which it rotates, means for rotating it 15 and a guide bearing normally out of contact with the cage at the top.

2. In a crushing machine the combination with a rotatable shaft of a core mounted thereon, said core having a pair of upwardly diminishing truncated conical surfaces, an annular member supported on the lower larger surface, a wedge collar having truncated conical surfaces in engagement with one of the surfaces on said core and in 25 engagement with the member and means for forcing said wedge into said member to lock it in position on the core.

3. A rotary member comprising a cylindrical annular member having at either end 30 truncated conical surfaces, a core upon which said annular member is mounted, said core having one truncated conical surface in engagement with one surface on the annular member and a second truncated conical surface of lesser diameter than the remaining 35 surface on the interior of the annular member and means for locking said core and said member together.

4. A rotary member comprising a cylindrical annular member having at either end 40 truncated conical surfaces, a core upon which said annular member is mounted, said core having one truncated conical surface in engagement with one surface on the roller and a second truncated conical surface of lesser diameter than the remaining 45 surface on the interior of the annular member and means for locking said core and said member together, said means comprising an 50 annular wedge.

5. A rotary member comprising a cylindrical annular member having at either end 55 truncated conical surfaces, a core upon which said annular member is mounted, said core having one truncated conical surface in engagement with one surface on the roller and a second truncated conical surface of lesser diameter than the remaining surface on the interior of the annular member, means for locking said core and said member together, said means comprising an annular wedge 60 and means for forcing said wedge into the space between the core and jacket.

6. A rotary member for crushing machines comprising a shaft, a core thereon,

an annular member resting upon said core, conical surfaces upon said core and said annular member, and an annular wedge and means for forcing it into the space between said core and said member to lock them together. 70

7. In a ring roll crushing machine the combination of a horizontal crushing ring with an upright roll traveling therein and therealong said ring surface provided with 75 a series of transverse material holding channels downwardly diminishing in cross section.

8. In a ring roll crushing machine the combination of a horizontal crushing ring 80 with an upright roll traveling therein and therealong said ring divided into crushing zones one above the other and one provided with depressions to receive and hold the material. 85

9. In a ring roll crushing machine the combination of a horizontal crushing ring with an upright roll traveling therein and therealong said ring divided into crushing zones one above the other and one provided 90 with a series of transverse channels to receive and hold the material.

10. In a ring roll crushing machine the combination of a horizontal crushing ring with an upright roll traveling therein and 95 therealong said ring divided into crushing zones one above the other and one provided with a series of transverse channels to receive and hold the material, said channels downwardly diminishing in cross section. 100

11. In a ring roll crushing machine the combination of a horizontal crushing ring with an upright roll traveling therein and therealong said ring divided into crushing zones one above the other and one provided 105 with a series of transverse channels to receive and hold the material said channels formed with curved surfaces.

12. In a ring roll crushing machine the combination of a horizontal crushing ring with an upright roll traveling therein and therealong said ring divided into crushing zones one above the other and one provided 110 with a series of transverse channels inclined to the vertical to receive and hold the material. 115

13. In a ring roll crushing machine the combination of a horizontal crushing ring with an upright roll traveling therein and therealong said ring divided into crushing 120 zones one above the other and one provided with a series of transverse channels inclined to the vertical to receive and hold the material said channels downwardly diminishing in cross section. 125

14. In a ring roll crushing machine the combination of a horizontal crushing ring with an upright roll traveling therein and therealong said ring divided into crushing zones one above the other and one provided 130

- with a series of transverse channels inclined to the vertical to receive and hold the material said channels formed with curved surfaces.
- 5 15. In a ring roll crushing machine the combination of a horizontal crushing ring with an upright roll traveling therein and therealong the opposed surfaces of said ring and roll being upwardly diverging and the 10 ring surface provided with depressions to receive and hold the material.
16. In a ring roll crushing machine the combination of a horizontal crushing ring with an upright roll traveling therein and therealong the opposed surfaces of said ring and roll being upwardly diverging and the 15 ring surface provided with a series of transverse channels to receive and hold the material.
- 20 17. In a ring roll crushing machine the combination of a horizontal crushing ring with an upright roll traveling therein and therealong the opposed surfaces of said ring and roll being upwardly diverging and the 25 ring surface provided with a series of transverse channels to receive and hold the material such channels downwardly diminishing in cross section.
18. In a ring roll crushing machine the 30 combination of a horizontal crushing ring with an upright roll traveling therein and therealong the opposed surfaces of said ring and roll being upwardly diverging and the ring surface provided with a series of trans- 35 verse channels to receive and hold the material such channels formed with curved surfaces.
19. In a ring roll crushing machine the 40 combination of a horizontal crushing ring with an upright roll traveling therein and therealong the opposed surfaces of said ring and roll being upwardly diverging and the ring surface provided with a series of transverse channels inclined to the vertical 45 to receive and hold the material.
20. In a ring roll crushing machine the combination of a horizontal crushing ring with an upright roll traveling therein and therealong the ring surface divided into 50 zones one above the other the opposed surface of said ring and roll being upwardly diverging and one zone of the ring surface provided with depressions to receive and hold the material.
- 55 21. In a ring roll crushing machine the combination of a horizontal crushing ring with an upright roll traveling therein and therealong the ring surface divided into 60 zones one above the other the opposed surfaces of said ring and roll being upwardly diverging and one zone of the ring surface provided with a series of transverse channels to receive and hold the material.
- 65 22. In a ring roll crushing machine the 65 combination of a horizontal crushing ring with an upright roll traveling therein and therealong the ring surface divided into 70 zones one above the other the opposed surfaces of said ring and roll being upwardly diverging and one zone of the ring surface provided with a series of transverse channels to receive and hold the material said channels downwardly diminishing in cross section.
23. In a ring roll crushing machine the 75 combination of a horizontal crushing ring with an upright roll traveling therein and therealong the ring surface divided into zones one above the other the opposed surfaces of said ring and roll being upwardly 80 diverging and one zone of the ring surface provided with a series of transverse channels to receive and hold the material said channels formed with curved surfaces.
24. In a ring roll crushing machine the 85 combination of a horizontal crushing ring with an upright roll traveling therein and therealong the ring surface divided into zones one above the other the opposed surfaces of said ring and roll being upwardly 90 diverging and one zone of the ring surface provided with a series of transverse channels inclined to the vertical to receive and hold the material.
25. In a ring roll crushing machine the 95 combination of a horizontal crushing ring having a surface across which the material is free to slide continuously with an upright roll revolving therein and therealong and means for feeding a film of material to the 100 ring surface so that the roll engages a film of continuously moving material the crushing surface of the ring provided with depressions for holding the material.
26. In a ring roll crushing machine the 105 combination of a horizontal crushing ring having a surface across which the material is free to slide continuously with an upright roll revolving therein and therealong and means for feeding a film of material to 110 the ring surface so that the roll engages a film of continuously moving material the crushing surface of the ring provided with transverse holding channels.
27. In a ring roll crushing machine the 115 combination of a horizontal crushing ring having a surface across which the material is free to slide continuously with an upright roll revolving therein and therealong and means for feeding a film of material to 120 the ring surface so that the roll engages a film of continuously moving material the crushing surface of the ring provided with transverse holding channels downwardly decreasing in cross section.
28. In a ring roll crushing machine the 125 combination of a horizontal crushing ring having a surface across which the material is free to slide continuously with an upright roll revolving therein and therealong and 130

means for feeding a film of material to the ring surface so that the roll engages a film of continuously moving material the crushing surface of the ring provided with transverse holding channels inclined to the vertical.

29. In a ring roll crushing machine the combination of a horizontal crushing ring having a surface across which the material 10 is free to slide continuously with an upright roll revolving therein and therealong and means for feeding a film of material to the ring surface so that the roll engages a film of continuously moving material the crushing surface of the ring provided with transverse holding channels formed with curved surfaces.

30. In a ring roll crushing machine the combination of a horizontal crushing ring 20 with an upright roll traveling therein and therealong and feed pockets radially disposed about the top of the ring.

31. In a ring roll crushing machine the combination of a horizontal crushing ring 25 with an upright roll traveling therein and therealong said ring surface provided with a series of transverse channels to receive and hold the material and feed pockets radially disposed in register with said trans-

30 verse channels.

32. In a ring roll crushing machine the combination of a horizontal crushing ring with an upright roll traveling therein and therealong and feed pockets radially disposed about the top of the ring and centrifugal means for discharging the material 35 into said pockets.

33. In a ring roll crushing machine the combination of a horizontal crushing ring 40 with an upright roll traveling therein and therealong said ring surface provided with a series of transverse channels to receive and hold the material and feed pockets radially disposed in register with said transverse 45 channels and centrifugal means for discharging the material into said pockets.

34. In a ring roll crushing machine the combination of a horizontal crushing ring with an upright roll traveling therein and 50 therealong and a collar located above said ring and having inwardly extending radially disposed partitions projecting therefrom above the ring to form pockets and centrifugal means for discharging the material 55 into said pockets.

35. In a ring roll crushing machine the combination of a horizontal crushing ring with an upright roll traveling therein and therealong and means for feeding by 60 centrifugal force a film of material toward the upper edge of the ring and radial plates

about the upper edge of the ring to stop the spiral motion of the material and direct its particles downwardly.

36. In a ring roll crushing machine the combination of a horizontal crushing ring 65 with an upright roll traveling therein and therealong and feed pockets radially disposed about the top of the ring and means for distributing material in substantially 70 equal quantities to said feed pockets.

37. In a ring roll crushing machine the combination of a horizontal crushing ring 75 with an upright roll traveling therein and therealong and feed pockets radially disposed about the top of the ring and means comprising a radial disk and fixed conical feed apron for distributing material to all of said pockets.

38. In a ring roll crushing machine the 80 combination of a horizontal crushing ring with an upright roll traveling therein and therealong a cylindrical housing for said ring open at the top and a conical feeding apron within said housing adapted to discharge material peripherally adjacent to the wall thereof and a part provided with feed pockets located beneath said apron and discharging into said ring.

39. In a ring roll crushing machine the 85 combination of a horizontal crushing ring with an upright roll traveling therein and therealong and a feed device to feed a continuous cylindrical film of material between their opposed crushing surfaces an open 90 chamber and a discharge way leading therefrom below the ring and means for simultaneously causing the roll to travel around the ring to move toward the ring and to rotate on its own axis said ring provided 95 with holding surfaces to receive the material.

40. In a ring roll crushing machine the combination of a horizontal crushing ring 100 with an upright roll traveling therein and therealong and a feed device to feed a continuous cylindrical film of material between their opposed crushing surfaces an open chamber and a discharge way leading 105 therefrom below the ring and means for simultaneously causing the roll to travel around the ring to move toward the ring and to rotate on its own axis said feeding device containing a centrifugal feeder plate and said ring provided with distributing pockets. 110

In testimony whereof, I affix my signature in the presence of two witnesses this 19th day of April 1913,

EDGAR B. SYMONS.

Witnesses:

F. A. OTTO,

FLORA REINHOLD.
